UNITED STATES PATENT OFFICE.

FRANK DUTCHER, OF VERSAILLES, PENNSYLVANIA, ASSIGNOR TO CENTRAL RAILWAY SIGNAL COMPANY, OF PITTSBURGH, PENNSYLVANIA, A CORPORATION OF NEW JERSEY.

RAILWAY SIGNAL-TORPEDO.

1,296,494.

Specification of Letters Patent.

Patented Mar. 4, 1919.

Application filed October 18, 1918. Serial No. 258,716.

To all whom it may concern:

Be it known that I, FRANK DUTCHER, a citizen of the United States, residing at Versailles, in the county of Allegheny and State of Pennsylvania, have invented certain new and useful Improvements in Railway Signal-Torpedoes, of which the following is a specification, reference being had therein to the accompanying drawing.

10 This invention relates to improvements in railway signal torpedoes, and it pertains to that type of torpedo which has become known in the trade as "paper" or "fiber" or "non-flying."

15 The object of my present invention is to provide an improved form of case combined with a novel way of connecting a rail-engaging member thereto.

In the accompanying drawing—

20 Figure 1 is an inverted plan view of a torpedo embodying my invention.

Fig. 2 is a vertical sectional view of Fig. 1, taken in the direction transverse the rail-engaging member.

25 Fig. 3 is a vertical sectional view taken through the case longitudinal the rail-engaging member.

Fig. 4 is a detached perspective of the ring or side wall of the case, with the rail-engaging strap shown in dotted lines.

30 The case of this improved torpedo comprises a ring 1, which forms the side wall of the explosive containing case, a disk 2 which forms the top of the case, and a disk 3 which forms the bottom of the said case. The explosive compound 4 is placed between these disks and is preferably of the tablet form.

As shown, the ring of said wall 1 of the case projects below the bottom 3.

40 The ring 1, is provided with oppositely arranged openings 5, through which a rail-engaging member 6 passes. These openings 5 are preferably closed all around, though they may be made in the form of notches and still embody the generic improvement.

45 The disks 2 and 3 may be secured within the ring in any suitable manner, but as here shown, the ring is provided with narrow

peripheral burs or flanges 7 at opposite edges, with a ring of water-proof cement 8, 50 at the periphery of the top disk 2.

A water-proof cement 9 substantially fills the depression or space formed by the extension of the ring or side-wall 1, below the bottom 3. This cement 9 serves to hold more 55 firmly the bottom 3 in place and to make a water-tight joint between the periphery of the disk 3 and the ring 1. The cement 9 also serves to cement the strap 6 to the bottom 3 and prevent the strap from having an end- 60 wise movement.

While I have here shown a circular form of case, I desire it to be understood other shaped cases may be used, such as an angular one without affecting the scope of the in- 65 vention.

Having thus described my invention what I claim and desire to secure by Letters Patent is:

1. An improved railway signal torpedo, 70 comprising an explosive containing case having a side-wall extending below the bottom of the case, the extended side wall having oppositely arranged openings, a rail-engaging member passing through the openings and parallel to the bottom, and a cementing uniting the strap to the said bottom. 75

2. An improved railway signal torpedo comprising an explosive containing case having its side wall extending below the bottom of the case, the extended wall having oppositely arranged openings, said openings having a bottom wall, and a rail-engaging member passing through the said openings and below the bottom. 80

3. An improved railway signal torpedo comprising a case, composed of a ring, disks within the ring, one forming the top and the other the bottom of the case, the ring projecting below the said bottom, the ring 90 having oppositely arranged openings with the lower walls, and a rail-engaging member passing through the openings and parallel to the bottom. 85

4. An improved railway signal torpedo 95 comprising a case, composed of a ring and

two disks within the ring, one disk forming the top and the other the bottom of the case, the ring projecting below the said bottom, the projecting portion of the ring having oppositely arranged openings, a rail-engaging member passing through the openings and parallel to the bottom and a cement filling the bottom space between the bottom

and the extension of the ring for holding the ring and the strap in position.

In testimony whereof I hereunto affix my signature in the presence of two witnesses.

FRANK DUTCHER.
